UNITED STATES PATENT OFFICE.

EUGENE PRINGLE, OF GLOVERSVILLE, NEW YORK, ASSIGNOR TO BRADT & SHIPMAN, OF DE KALB, ILLINOIS.

STUD MEMBER FOR DETACHABLE FASTENERS.

SPECIFICATION forming part of Letters Patent No. 628,035, dated July 4, 1899.

Original application filed April 22, 1896, Serial No. 588,585. Divided and this application filed March 3, 1898. Serial No. 672,370. (No model.)

To all whom it may concern:

Be it known that I, EUGENE PRINGLE, a citizen of the United States, residing at Gloversville, in the county of Fulton and State of New York, have invented certain new and useful Improvements in Stud Members for Detachable Fasteners; and I do hereby declare the following to be a full, clear, and exact description of the invention, such as will

enable others skilled in the art to which it appertains to make and use the same.

The present invention relates to separable buttons or fastening devices such as are employed on gloves and other articles; and this application is a division of an application filed by me April 22, 1896, Serial No. 588,585, which has since resulted in Patent No. 600,114, dated March 1, 1898, and in which were originally shown, described, and claimed both socket and stud members of a separable button. That application has been restricted to the socket member, and the present application relates to the stud member.

The principal object of the invention is to provide a construction of stud member wherein the parts thereof may be effectively united by upsetting or crimping one within the other, while at the same time permitting the use of a comparatively thin outer shell of bulb form and wherein the parts will accommodate themselves to varying thicknesses of material without in the least impairing the clenching or crimping effect.

The invention entirely overcomes the difficulties heretofore encountered in the manufacture of stud members for separable buttons arising out of attempts to effect a clenching or crimping action by forcing together a pointed rivet and a bulb-form shell, in which case the point of such rivet either enters the slit which may already exist in the shell or makes an opening for itself and breaks open the shell. This difficulty has made necessary the employment of a special clenching-piece within the bulb-form shell; but my invention obviates any such necessity, while at the same time removing the objection to the pointed rivet when used without a clenching-piece.

With the above-stated objects in view the invention consists in certain novel features

of construction and combinations of parts, the essential elements of which are recited in the appended claims and a detailed description of preferred forms of embodiment of which is hereinafter given.

55

The drawings which accompany and form part of this specification illustrate different forms in which the invention may be embodied.

Of said drawings, Figures 1 and 2 represent completed stud members in cross - section, illustrating different clenching effects which may result in the joinder of the two parts of the stud member. Fig. 3 represents the bulb-form shell or head in cross-section. Fig. 4 represents the rivet member in cross-section. Fig. 5 represents a complete separable button or fastening device in cross-section, showing my invention embodied therein; and Fig. 6 represents a modified form of rivet, also in cross-section.

In the drawings, the letter *k* designates a hollow bulb-form head or shell having a base-flange *k'* and a catch-groove or annular recess *k''* thereabove, and the letter *l* designates a round top or obtuse-ended rivet having a base-flange *l'* and provided with a slit *m*, extending part way through its length from the upper end, as clearly shown in Fig. 4. A hole having been previously provided in the material, when the rivet is passed through the same and into the hollow head the upper slitted portion is crimped or upset within said head, as shown in Fig. 1, or under certain conditions the upset end of the rivet may assume the shape shown in Fig. 2 or any irregular or crinkled or burred form which will insure the secure attachment of the stud to the material, and the burred or crinkled portion being concealed within the hollow portion of the head of the stud the appearance thereof is not marred or disfigured by rough or unsightly exterior projections. It will also be noted that the attaching-rivet may be comparatively long, thus permitting considerable variation in range of thickness of material to be used without alteration in the length or shape of either the rivet or head portion of the stud, as the amount or extent to which the end of the rivet will be burred will de-

pend upon the distance between the flanges of the two members comprising the stud, and this distance will conform to the thickness of material clamped between them by the pressure of the upsetting-tools.

It has been extremely difficult heretofore to attach a slitted or resilient stud member to the material by means of a rivet or eyelet which passed up into the hollow portion of the stud-head, owing to the liability of the pointed end of the rivet or the edge of the eyelet catching into the edges of the slit, and thus spreading, perforating, or changing the shape of the stud-head. Owing to this difficulty it has been customary to use a separate clenching-piece in such slitted studs to upset the end of the rivet or eyelet. In fact, slitted studs have not heretofore been attached to the material by the use of an eyelet or rivet alone without a clenching-piece, especially when said rivet is to be upset by pressure of the head of the rivet against the inner surface of the stud-head. One of the especial advantages arising from the use of my rivet is that a stud of comparatively thin material may be attached to the fabric, and the upset or crinkled end of the rivet serves as a reinforcement, owing to the fact that it conforms to the interior shape of the stud-head and backs it up, while it also adds to its spring action, if slitted, as it sustains and reinforces the spring-walls of the stud-head.

If an unslotted head is used, it can be made of light material, as in this class of fasteners, many of which are used on thin gloves, weight has much to do with the selection and practicability of a fastener, as from two to ten of these fasteners are used on a pair of gloves. Further, if quite thin material is used in the stud-head, owing to the fact that the top of the fastening-rivet is rounded and slitted and thereby weakened the finish of the stud-head is not injured nor the material dented, distorted, or marred during the setting operation, of which there would be danger in using other forms of fastening-rivets. The top end of my rivet being slitted and thus weakened when it strikes the inner surface of the stud-head is readily crinkled and folded upon itself within the head and above the groove, thus insuring a permanent attachment to the material and allowing for a very considerable range of thickness of material to which the stud may be attached, and with my rivet the outer surface of the head of the stud is always smooth and the material is tightly held between the flanges of the bulb-form head and rivet. I may find it desirable to make more than one slit in the rivet, and I may use a solid slotted rivet, as shown in Fig. 6. If desired, the stud member *k* may be slotted to form a spring-post, as indicated by dotted lines in Fig. 3.

In Fig. 5 I have shown a stud member of the above description together with and in its fastening relation to a socket member of a construction shown in my original applica-

tion above mentioned, and it will be seen that the two members so conform with each other in their interlocking and contacting portions as to effectually obviate a wabbling action between them. It may be added, however, that while the stud member herein described is admirably adapted for use with the forms of socket members shown and described in my original application it is nevertheless capable of conjoint use with other forms of socket members.

Having thus fully described my invention, what I claim as new, and desire to secure by Letters Patent of the United States, is—

1. A stud member of a separable fastener consisting of a hollow bulb-form head having a base-flange designed to be secured upon one side of the material, and a fastening-rivet therefor; said rivet having a base-flange and an elongated shank formed with an obtuse end slitted as described and adapted to be passed through a previously-formed hole in the material and into said head and upset against the inner surface thereof, thus invisibly securing the stud to the material, whereby a thin shell may be used for the head of the stud and the head and rivet effectively united without deforming or breaking said head, substantially as described.

2. A stud member for separable fasteners composed of a hollow bulb-form head having a base-flange and an external socket-member-engaging groove or annular recess above said flange, combined with a hollow flanged fastening-rivet having the upper end of its shank slitted and formed with a blunt upper end; said slitted shank being adapted to pass through a previously-formed hole in the material into said head and to be upset therein, as and for the purpose set forth.

3. In a separable fastener, the socket member in combination with a stud member comprising a suitable hollow head having a base-flange and a catch-groove below said head, and a slotted fastening-rivet having a round or obtuse slitted end and a base-flange; said end being bent or folded within said hollow head and firmly clamping the material between the flanges of the head and rivet, substantially as described.

4. A stud member for separable fasteners composed of a hollow bulb-form head provided with a base-flange and an external socket-member-engaging groove or annular recess above said flange, combined with a base-flanged fastening-rivet having a stem rising from said flange and provided with a round or obtuse end and slotted through said end to allow it to easily spread or upset within the hollow head of said stud and firmly clamp the material between the flanges of the head and rivet.

5. In a separable fastener, the socket member, in combination with a stud member comprising a suitable hollow head adapted to fit said socket member and having a base-flange and a catch-groove below said head, and a

fastening-rivet having a blunt upper end slotted to weaken it and thereby allow it to readily spread and conform to the inner surface of the stud-head, thus firmly securing the stud to the material without deforming the head of the stud, substantially as and for the purpose set forth.

In testimony whereof I affix my signature in presence of two witnesses.

EUGENE PRINGLE.
